UNITED STATES PATENT OFFICE.

CHRISTOPHER B. HERMAN, OF NORWICH, KANSAS.

STOCK-CAR.

SPECIFICATION forming part of Letters Patent No. 425,790, dated April 15, 1890.

Application filed May 22, 1888. Serial No. 274,762. (No model.)

To all whom it may concern:

Be it known that I, CHRISTOPHER B. HERMAN, of Norwich, in the county of Kingman and State of Kansas, have invented a new and useful Improvement in Stock-Cars, of which the following is a specification.

The object of my invention is to provide an improved stock-car for the transportation of all kinds of live stock, and designed especially for the convenient loading of the car, the proper balancing of the load, the feeding and watering of the stock in transit, and the general comfort and improved condition of the stock when delivered.

15 It consists in the peculiar construction and arrangement of the car, which I will now proceed to fully describe, reference being had to the accompanying drawings, in which—

Figure 1 is a side elevation of one end of 20 the car. Fig. 2 is a horizontal section through the same. Fig. 3 is a vertical cross-section through lines $\alpha\alpha$ of Fig. 1 and yy of Fig. 2. Fig. 4 is a plan view with the roof of the car removed, and Fig. 5 is a detail of a sliding 25 shutter for closing up the car tightly in cold weather.

A A A, Figs. 2 and 3, represent a series of vertical posts arranged in the middle line of the car and supported at their upper ends by 30 iron braces K K, which extend divergently upward and connect with the rafters of the roof of the car by means of screws. These posts are spaced far enough apart to form stalls for the stock running crosswise the car.

35 To each of these posts are attached two folding doors or gates B B, said doors being connected to the post as a hinging point and having their free outer ends adapted to be either fastened to the sides of the car to form 40 transverse partitions between the stalls or be folded back along a central longitudinal line, as shown by dotted lines, which forms two alley-ways, one on each side of the car. These partitions are arranged about thirty-four 45 inches apart or just far enough apart to permit the largest sized animal to lie down, thus avoiding the necessity of stopping the train and unloading the animals to rest them. These doors are constructed in the form of lattice-work of vertical and horizontal strips of flexi-

ble material, like rubber belting or leather or similar stuff, rubber belting being preferred. The horizontal strips are nailed to opposite sides of the post A, and extend from the free end of one gate to the free end of 55 the other, while the vertical strips are riveted between the horizontal strips. The object in making these lattice doors flexible is to permit them to be rolled or folded into a smaller space than the radius of a stiff door, 60 which is very necessary in carrying out my method of loading, as hereinafter described. Another object is to prevent the bruising of the animal from the jerking of the car in starting and stopping. These doors are fastened to the sides of the cars as follows: At 65 the ends of the horizontal strips forming the doors the material is bent upon itself to form loops a, and through these loops passes a vertical key-rod C, that also passes through a 70 series of eyes or staples b on a vertical bar D, which forms a rigid outer end of the door to fasten it when closed or support it when open. These bars are secured to the sides of the car when the doors are closed by having their 75 lower ends seated in rigid stirrups or loops E' projecting from the sides of stanchions F, attached to the inner wall of the car; while a corresponding stirrup or loop E is pivoted or hinged to the same stanchion at the top, so 80 as to drop over the end of the bar D and secure it at the top.

To prevent wild cattle from attempting to jump over the flexible partitions, triangular guards L are arranged above each partition 85 and are connected each to the middle post A, stanchion F, and the roof-rafter, which guards also serve to strengthen and brace the car.

On one side of each stall in the car is pivoted between the stanchions F F a feed-trough G and water-trough G², both made as one, with a middle partition, which feed and water trough is arranged to be dumped, as shown by dotted lines, to empty the contents outside of the car. On the side of the car 95 upon which these troughs are carried the panel of the stall is not slatted or open, but is constructed with a blind or imperforate panel, as shown at I, Figs. 1 and 3, the alternate panels I' at the tails of the animals being 100

open or slatted. The object of this is as follows: Most of the cattle shipped are wild from the plains and all are more or less timid when on the cars, and when the animal is able to see through the slats of the car in front the passing of trains so terrifies the animals that they will back to the end of the stall and keep away from food and drink and so suffer from hunger and thirst as to involve the very objections which stock-cars seek to avoid; hence I make the front panel of each stall imperforated or perfectly blank, so that the animal cannot see through the side of the car and is encouraged to take its food and drink.

15 Near the bottom of the car upon each side of each stall are the lower troughs G'. These are designed for hogs and sheep, and, except when such small stock is being transported, said lower troughs are turned up outside of the car, as shown in Fig. 3.

H is a hinged door at the tail end of each stall, through which the filth in the stall may be cleaned out.

20 On top of the posts A and extending longitudinally through the car is a foot-board J, which, with hand-rails O O on the braces K, form a central alley-way or passage at the top of the car to permit persons to traverse the car, when filled with live stock, from end to end, so as to feed or inspect them.

25 Access to the alley-way is had through an elevated door R in the end of the car. On a level of this alley-way and at the head of each stall is a hay-rack M, and at the tail end of the stall and in a corresponding position is the water-reservoir N and grain-reservoir N', Figs. 3 and 4, separated by a partition.

30 The water-trough G of each stall (except the end stall) receives its water from the water-tank N at the tail end of the adjacent stall on one side, and the feed-trough G² receives its grain from the grain-reservoir N' at the tail end of the adjacent stall on the opposite side, and so the water and grain reservoir at the tail end of each stall is made to deliver water and grain to the troughs at the front ends of the adjacent stalls through spouts controlled by valves P, Fig. 3.

35 The operation of loading my stock-car is as follows, (see Fig. 2.) The car is formed with two entrance-doors, No. 1 and No. 2, about the middle of its side. All the flexible doors B (except those between the entrance-doors No. 1 and No. 2) are bent back, as shown by dotted lines, so as to form two alley-ways upon opposite sides of the middle of the car. One of the flexible doors B between the entrance-doors is left closed and the other is bent back one hundred and eighty degrees or parallel 40 to the closed door. The two entrance-doors now communicate with the two alley-ways, and when two animals enter the car from the gang-plank animal No. 1 enters through door No. 1 and passes straight to the end stall and 45 has the first set of doors B B closed upon

him, while animal No. 2, entering through door No. 2, passes to the alley-way upon the opposite side of car, proceeds to the second stall, and is secured by the second set of doors B B. The third animal, entering door 50 No. 1, passes to the third stall, and so on. When the ends of the cars are thus filled, the two stalls opposite doors No. 1 and No. 2 are then filled, and for this purpose door No. 1 is closed by the usual slide from the outside, and 55 an animal is driven into door No. 2 and is made to turn into the next stall with his head next to door No. 1, and, the partition being closed on him, another animal is then driven in door No. 2 and the latter closed as soon as 60 his body is within the stall. It will thus be seen that in this method of loading each animal is obliged to move straight ahead to his stall without any opportunity to dart sidewise or attack the drivers, and the animals are 65 loaded with head and tail alternating, so as to balance the car and make it bear equally upon both sides of the truck.

70 To close in my stock-car in cold winter weather, so as to protect the stock, I employ at the tail end of each stall a sliding shutter S, Fig. 5, made of sheet metal, and whose bars and openings correspond to the openings and slats of the side of the car, and which shutter is arranged to have an adjustment in vertical 75 guides, so that a slight adjustment will throw its openings into registration with the openings between the car-slats when open ventilation is desired, or to have its bars closed over the openings in the sides of the car when a 80 tight or close car is required.

85 I am aware that the general features of my invention are not, broadly, new, and I therefore only claim my peculiar construction and arrangement of parts.

90 Having thus described my invention, what I claim as new, and desire to secure by Letters Patent, is—

95 1. The combination, in a stock-car, of a central row of posts A, having gates B hinged thereto, a longitudinal foot-board J, arranged upon the top of the row of posts, and braces K, extending therefrom to the roof of the car, substantially as shown and described.

100 2. The combination, in a stock-car, of a central row of posts A, having flexible gates B hinged thereto, a longitudinal foot-board J, arranged upon the top of the posts, braces K, extending therefrom to the roof of the car, receptacles M N, for food and drink, arranged in the upper corners of the car, triangular guards L, filling the spaces between the receptacles and the braces, and feed-troughs arranged in the stalls and connected with the receptacles for food and drink, substantially 105 as shown and described.

110 3. The combination, with a stock-car having a series of transverse partitions, of a series of food and water troughs G and G², arranged at the head of each stall, and a series 115

of grain and water reservoirs N N', arranged at the tail of each stall, the heads of the stalls being alternately reversed, and the grain and water reservoirs at the tail of each stall being provided with spouts arranged to deliver their contents into the grain and water compartments of the troughs at the head of the next adjacent stalls, substantially as and for the purpose described.
